UNITED STATES PATENT OFFICE

DAVID G. DEDRICK, OF GROTON, CONNECTICUT

SOUNDING DEVICE

Application filed September 12, 1929. Serial No. 392,152.

The present invention relates to sounding devices or leads for ascertaining the depths and conditions of the beds of oceans and other water-ways, and for collecting specimens and samples thereof.

The object of the invention includes means in the form of a scoop or cup movably mounted in the base of the lead and acting upon contact with the water-bed to collect and hold relatively soft or loose particles or samples of which the bed may be formed.

A further object is to provide resilient means normally acting to effect a joint collecting and closing movement of the cup.

Also, to provide a detent adapted to hold the cup in open position in opposition to said resilient means, and to provide tripping means for said detent operable upon contact with the water-bed.

Also, to provide an arrangement whereby the working parts are essentially disposed within the body of the lead and protected thereby against injury.

For further comprehension of the invention, and of the objects and advantages thereof, reference is had to the following description and accompanying drawing, and to the appended claims in which the various features of the invention are more particularly pointed out.

Referring to the drawing in which similar characters of reference designate like parts throughout the several views:

Figure 1 of the drawing is a side elevational view of a sounding lead embodying my invention.

Figure 2 is an elevational view showing the base portion of the lead taken at right angles to Fig. 1.

Figure 3 is an elevational view of the base portion of the lead with the cover-plate removed to show the operating parts.

Figure 4 is a sectional elevation of the base taken on the line 4-4 of Fig. 5.

Figure 5 is a transverse sectional view of the base portion of the lead taken on the line 5-5 of Fig. 4.

Numeral 10 of the drawing illustrates the lead or weight connected to the sounding-line 11, the base or bottom face of the lead being

provided, as herein shown, with a semi-spherical recess 12. In the opposite side walls of the latter is rotatively mounted a spindle 13, having fixed at one end thereof a swinging lever-arm 14, and at its opposite end a hand-grip 15, by means of which the spindle may be turned a portion of a revolution. Upon the spindle is fixedly mounted a semi-spherical closure cup 16 adapted to freely turn within the recess 12 of the lead, the inner edges of the cup being beveled as at 17 for a portion of its distance around to serve as a cutting or scooping edge, the remaining portion forming a squared edge at 18, adapted to seat against the inner edge of the packing-ring 19 when the cup is in open position. The inner face of the packing-ring is shaped to slidably engage the outer surface of the cup during its part rotation and effect a substantially close joint therebetween, a seat being also provided along the bottom edge of the packing-ring at 20 to effect a close joint when the cup is in closed position, as shown in the dotted lines 21 in Fig. 4.

For operating the cup a side recess 22 is formed in the base of the lead and adapted to be closed by the cover-plate 23 and form a chamber to receive the swinging lever-arm 14. A spring 24 is also positioned within the side recess or chamber 22, one end of the spring being connected to the arm 14 by the pin 25, while its opposite end is fixed to the lead base by the pin 26. The tension of the spring in its straight-line position below the axis of the spindle 13, as shown in Fig. 3, serves to urge and hold the cup in open position against the inner edge of the packing-ring 19, indicated at 18 in Fig. 4. The cup is also held normally in open position by a trip-rod 27, endwise slidable within the base of the lead and is provided with a projecting stop-pin 28 that extends into the recessed chamber 22 and is adapted to freely engage the lower edge of the arm 14 while the cup is closed. In this latter position of the cup the trip-rod projects below the bottom face of the lead and is adapted during the sounding operation to engage the water-bed, whereby the weight of the lead forces the trip-rod 27 to move inwardly thereof, causing the

stop-pin 28 to upwardly force the arm 14 against the downwardly closing action of the spring 24, the upward movement of the arm serving to raise the straight-line action of the spring above the axial center of the spindle and in which position it is free to act and resiliently effect the closing movement of the cup.

In the closing movement of the cup its beveled edge acts to cut away, scoop up and securely enclose relative loose substances with which it engages, and by the resilient movement in which the work is accomplished substantially no time is allowed for the lead to turn about its base and interfere with the desired result to be obtained.

In the closed position of the cup as shown in full lines in Figs. 1 and 2 and in dotted lines in Fig. 4, the cup arm 14, shown in full lines in Fig. 3, assumes the dotted-line position 14^a and the position of the connected spring 24 the dotted line position 24^a.

It is to be understood that detail changes in the structure of the device may be made without departing from the scope of the present invention.

What I claim as my invention and desire to secure by Letters Patent, is:

1. A sounding lead having in its bottom face a recess, a closure cup mounted to turn within said recess and provided with a beveled closing edge, resilient means normally acting to close said cup, means arranged to hold said cup in open position in opposition to said resilient means, and a trip-rod adapted to release said resilient means and close said cup.

2. A sounding lead having in its bottom face a recess, a spindle mounted to turn in the opposite side walls of said recess, a closure cup fixed to said spindle within said recess, resilient means normally acting through said spindle to close said cup, means arranged to hold said cup in open position in opposition to said resilient means, and a trip-rod adapted to release said resilient means and close said cup.

3. A sounding lead having in its bottom face a recess, a spindle mounted to turn in the opposite side walls of said recess, a closure cup fixed to said spindle within said recess, an arm for rotating said spindle, resilient means normally adapted to rotate said spindle through said arm and close said cup, and means for rotating said spindle in opposition to said resilient means and opening said cup.

4. A sounding lead having in its bottom face a recess, a spindle mounted to turn in the opposite side walls of said recess, a closure cup fixed to said spindle within said recess, an arm for rotating said spindle, resilient means connected to said arm and normally adapted to rotate said spindle and close said cup, means for rotating said spindle in op-

position to said resilient means for opening said cup, a chamber formed in a side wall of said lead and disposed to receive said operating arm and resilient connections, and a cover-plate for said chamber.

5. In a sounding lead having in its bottom face a recess, a closure cup mounted to turn within said recess, resilient means normally acting to close said cup, means arranged to open said cup in opposition to said resilient closing means, and packing disposed within said recess and adapted to seal said cup in its open and closed positions with respect to said recess.

6. In a sounding lead having in its bottom face a semi-spherical recess, a semi-spherical closure cup mounted to turn within said recess, resilient means normally acting to close said cup, means arranged to hold said cup in open position in opposition to said resilient means, and a trip-rod adapted to release said resilient means and close said cup.

Signed at New York in the county of New York and State of New York this sixth day of September, A. D. 1929.

DAVID G. DEDRICK.
